PORTABLE FIRE PLACE GRATE.

No. 18,895.

Patented Feb. 5, 1889.

UNITED STATES PATENT OFFICE.

EDWARD L. CALEY, OF PHILADELPHIA, PENNSYLVANIA, ASSIGNOR TO
GILBERT COMBS, JOHN BAWDEN, AND JOHN H. BAWDEN, OF SAME
PLACE.

DESIGN FOR A PORTABLE FIRE-PLACE GRATE.

SPECIFICATION forming part of Design No. 18,895, dated February 5, 1889.

Application filed January 9, 1889. Serial No. 295,883. Term of patent 7 years.

To all whom it may concern:

Be it known that I, EDWARD L. CALEY, a citizen of the United States, and a resident of Philadelphia, Pennsylvania, have invented a new and original Design for a Portable Fire-Place Grate, of which the following is a specification.

My design for a fire-place grate is fully shown in the accompanying photographic illustration.

The design of the back and side plates is of a floral character, and the design of the front plate is in imitation of lattice-work. In the center of the back plate is a foliated scroll 15 surrounded by a plain quadrangular border-line with scalloped corners. Above and below the border are lines formed of small dashes. Surrounding the panel thus formed is a border composed of leaves and flowers, and on

each side of the small panel, inside the outer border, is a scroll design.

The designs of the side plates are of similar character to those of the back plate.

The design of the front plate is composed of a series of longitudinal and vertical bars, 25 forming a series of quadrangular spaces.

I claim—

The design for a fire-place grate, substantially as described, and as shown in and by the accompanying photographic illustration. 30

In testimony whereof I have signed my name to this specification in the presence of two subscribing witnesses.

EDWARD L. CALEY.

Witnesses:

WILLIAM D. CONNER,
HARRY SMITH.

It is hereby certified that the residence of the assignees in Design Letters Patent No. 18,895, granted February 5, 1889, upon the application of Edward L. Galey, of Philadelphia, Pennsylvania, for a Design for a "Portable Fire-Place Grate," was erroneously written and printed "of same place," whereas said residence should have been written and printed *of Freehold, New Jersey*; and that the said Letters Patent should be read with this correction therein that the same may conform to the record of the case in the Patent Office.

Signed, countersigned, and sealed this 12th day of February, A. D. 1889.
